FISH LURE

Raymond J. Fisher, Racine, Wis.

Application September 15, 1948, Serial No. 148,591

Term of patent 7 years

(Cl. D31—4)

To all whom it may concern:

Be it known that I, Raymond J. Fisher, a citizen of the United States, residing at Racine, in the county of Racine and State of Wisconsin, have invented a new, original, and ornamental Design for a Fish Lure, of which the following is a specification, reference being had to the accompanying drawing, forming a part thereof, and in which:

Figure 1 is a top plan view of a fish lure showing my new design.

Figure 2 is a side elevation of my new design.

Figure 3 is a front elevation of my new design.

Figure 4 is a sectional view on the plane of longitudinal line IV—IV of Fig. 1.

Figure 5 is a sectional view on the plane of transverse line V—V of Fig. 4; and

Figure 6 is a bottom plan view of my new design.

I claim:

The ornamental design for a fish lure, as shown.

RAYMOND J. FISHER.
